CLAIM

The ornamental design for a pair of spectacles, as
shown and described.

DESCRIPTION

FIG. 1 is a front elevational view of a pair of spectacles
embodying my new design;

FIG. 2 is an elevational view of one side of the pair of
spectacles, the opposite side thereof being of substan-
tially the same appearance; and

FIG. 3 is a top plan view thereof, the temple being
broken away for convenience of illustration.
